UNITED STATES PATENT OFFICE.

LESLIE W. CLAYBOURN, OF CINCINNATI, OHIO.

METHOD OF AND APPARATUS FOR SHAVING PRINTING-PLATES.

1,282,013.

Specification of Letters Patent.

Patented Oct. 15, 1918.

Application filed March 12, 1917. Serial No. 154,242.

To all whom it may concern:

Be it known that I, LESLIE W. CLAYBOURN, a citizen of the United States, residing at Cincinnati, in the county of Hamilton and State of Ohio, have invented certain new and useful Improvements in Methods of and Apparatus for Shaving Printing-Plates, of which the following is a specification.

My invention relates to the art of shaving the under or bearing surfaces of printing plates, and it is the object of my invention to provide for rendering printing plates of uniform thickness throughout at their printing portions.

Printing plates cast or formed by any of the present well-known methods, are subject to undesirable irregularities in the thickness of the plates at their printing portions, caused for instance by uneven cooling and shrinking of the plates. These irregularities cause undue high or low places in the printing surface, or variations in the contour of the rear bearing face of the plate relative to the coöperating face of a plate bed or cylinder, as a result of which, the printed impression made by the plate has greater variations than is desirable in the imprint of the lines and different parts thereof, due to the over-variations in the pressure applied at the various parts of the printing surface of such plate when printing from the same.

An attempt may be made to counteract the undesirable results of such variations in the thickness of the plate, by the well-known methods of "overlaying" the tympan of a printing press or "underlaying" the plate in the printing press, as understood in the art, these methods being objectionable however, as being impermanent, time-consuming, and expensive.

It is the object of my present invention to so act on the printing plate and to provide means whereby the printing plate is reduced to a uniform thickness throughout at its printing portions, so that the necessity of "overlaying" or "underlaying" may be avoided or reduced to a substantial minimum.

The invention consists in supporting the printing plate at its printing surface by a rigid support, and shaving the rear face of the printing plate while applying pressure to said rear face in adjacency to the shaving

plate by a rigid support, and shaving the rear face thereof in interrupted lines while applying pressure to said rear face substantially coincident with the interruptions in the shaving lines.

The invention consists further in the provision of a rigid support for the printing plate, and shaving means for the printing plate comprising a cutting edge having a path of movement spaced throughout equally from the rigid support, and presser means adjacent the cutting edge adapted to urge the printing plate toward its rigid support.

The invention consists further in the provision of a flexible relatively non-compressible supporting means for a printing plate, and means for adjusting the distance between the shaving mechanism and the supporting means.

The invention will be further readily understood from the following description and claims, and from the drawings illustrating my improved exemplified apparatus, in which latter:

Figure 1 is an end elevation of the machine with the spokes of the operating hand-wheel partly broken away.

Fig. 2 is a plan view of the same with the spokes of the hand-wheel removed.

Fig. 3 is a vertical section taken on the line 3—3 of Fig. 2.

Fig. 4 is a detail taken on the line 4—4 of Fig. 3.

Figs. 5, 6 and 7, are details in vertical section taken on the lines 5—5 of Fig. 2, 6—6 of Fig. 5, and 7—7 of Fig. 6, respectively.

Fig. 8 is a detail fragmentary plan view of the shaving and presser means.

Fig. 9 is a detail fragmentary end elevation of the machine showing the positioning stop and clamping mechanism for the plate; and,

Fig. 10 is a vertical section taken on the irregular line 10—10 of Fig. 3, and partly broken away.

I have exemplified a machine for shaving curved printing plates, although parts of the invention are applicable to shaving flat printing plates.

A rigid support by which the printing plate is supported while the rear face thereof is being shaved is exemplified as a trough 11, the trough being instances as mounted upon suitable legs 12.

Shaving means and means for causing corrective shaving movement between the shaving means and support for the plate are provided, the shaving means being exemplified as the moving agency. In the present exemplification the shaving means extend lengthwise of the trough and are pivotally mounted relative thereto, so that by rotating the same, the shaving instrumentalities will be moved across the rear or concave face 17 of printing plate 18, exemplified as a curved printing plate, supported in trough 11, to shave the same, the printing plate being retained within the trough by an adjustable 15 positioning gage 20 and a coöperating clamp 19.

Trough 11 is exemplified as comprising a rigid curved wall 25 having outwardly extending edge-flanges 26, 27, and forming an 20 elongated body having an inner curved face 28, which is a sector of a cylinder. A flexible plate 29, instanced as of a material, such as brass, cross-sectionally non-yielding in comparison with the printing-plate, is received 25 within trough 11, preferably with adjusting layers, such as paper sheets 31, interposed between the inner face of the trough and the plate.

Sheets 31 of selective thicknesses are employed, depending on the character of the printing face, for producing proper impression of the printing lines thereon. The plate being flexible will adapt itself to the curvature of the surface upon which it is supported. The ends of the trough are instanced as closed by end-walls 35, preferably secured by bolts 37 to flanges 38 at the outer ends of the trough. Strengthening ribs, such as shown at 40, are preferably provided upon the outer face of the trough.

The shaving mechanism preferably comprises a support 44 having trunnions 45 at the ends thereof, the trunnions being instanced as journaled in bearings 47, formed upon the respective end-walls 35 of the trough and preferably projecting within the trough an appreciable distance as shown at 46. Suitable means are provided for rotating support 44 either by hand or power. These means are instanced as comprising a gear 48 secured to a trunnion 45 of support 44 beyond the proximate bearing 47, the gear being arranged to mesh with a pinion 49, preferably rotatively mounted upon a bracket 50 extending laterally from the proximate end-wall 35 of trough 11. Pinion 49 is instanced as secured to a hand-wheel 51 so as to be rotated thereby.

Support 44 is so journaled relative to trough 11, that during its rotation the path of movement of the shaving parts supported thereby is concentric with the cylinder of which face 28 of the trough is a sector, the 65 space between said path and said face 28

being in the form of the sector of a cylinder, and of uniform depth.

A ledge 54 upon which the shaving mechanism is mounted, is exemplified as projecting laterally from support 44. The outer 70 edge 53 of the ledge is suitably spaced from the face 28 of the trough so that when support 44 is rotated the ledge will clear the rear face 17 of a printing plate supported upon plate 29.

Ledge 54 is instanced as provided with a supporting face 55 upon which the shaving parts are mounted, and in order to provide sufficient space for lateral adjustment of the shaving parts relative to the ledge, the 80 face of support 44 proximate to supporting face 55 of the ledge, is preferably cut away, forming a plane surface 56 perpendicular to the supporting face 55 of the ledge. The ledge may be suitably braced as by outwardly extending ribs 57 connecting the face 58 of the ledge which is opposite supporting face 55, and the proximate surface of support 44.

The shaving parts mounted upon ledge 90 54 comprise knives 60, extending crosswise of the ledge and arranged in spaced relation lengthwise thereof, and pressure exerting devices adjacent the respective knives adapted to apply localized yielding pressure 95 to the rear face 17 of the printing plate over the area being acted on by the shaving knives. The shaving parts are preferably arranged to be adjusted laterally relative to the ledge 54, and toward and from the support for the printing plate. For this purpose the shaving parts are exemplified as including a bar 62, adjustably mounted upon the ledge, and to which knives 60 and the pressure exerting devices are secured.

Bar 62 is instanced as provided with a bearing-face 63 slidably contacting supporting face 55 of ledge 54, the bar preferably being adapted to be guided laterally relative to the ledge, and to be secured thereto at 110 adjusted positions by bolts 64. The bolts are exemplified as extending through suitable laterally extending slots 65 in ledge 54, with the ends of the bolts received in the bearing-face of bar 62 by threaded connections 66, and the heads 67 of the bolts, which may be provided with washers 68 arranged to contact face 58 of ledge 54, so that when the bolts are tightened, bar 62 will be rigidly clamped upon the ledge.

Bolts 73 are instanced as received, as by threaded connections 74, in face 56 of support 44, with the heads 75 of the bolts impinging against the proximate face 76 of bar 62, so that by turning the bolts the 125 lateral position of the bar 62 upon ledge 54 may be regulated.

The knives secured to bar 62 are instanced as each comprising a shank 79 having a transverse blade 80 at the end thereof, the 130

blade being provided with a cutting edge 81. The shanks of the knives are exemplified as received respectively in laterally extending grooves 82, formed in the face of bar 62 which is opposite bearing-face 63 thereof and which is represented at 83, the knives being removably secured to the bar as by screws 84 extending through the respective shanks 79. Grooves 82, and the knives secured therein, are arranged in spaced relation lengthwise of bar 62, so that the cutting edges 81 of the knives will form an interrupted cutting edge extending lengthwise of the supports.

15 The pressure exerting devices arranged to bear against the rear face of the printing plate, are exemplified as comprising independently spring pressed rods 88, laterally positioned relative to ledge 54 and provided with suitable contacting parts instanced as rollers 89. The rollers are journaled in yokes 90, and are respectively received in recesses 91 formed in face 83 of bar 62 between adjacent grooves 82, so that 20 the rollers are respectively positioned in the spaces between adjacent knives 60. The peripheral contacting surfaces of the rollers are preferably arranged to contact the printing plate by normally projecting slightly 25 beyond the interrupted cutting edge formed by knife-blades 80, at the interruptions therein.

In order that the pressure exerting devices may be removed as a unit from the 30 shaving mechanism, when so desired, as for example, when the knife or knives are to be sharpened, rods 88 are instanced as received respectively in laterally extending apertures 97 formed in a supporting bar 95, 35 which extends lengthwise of bar 62, and is detachably secured upon face 83 thereof in rear of recesses 91 as by bolts 96. Thus by detaching supporting bar 95 from bar 62, the pressure mechanism may be combinedly 40 removed from the machine, and by removing the bar 62 the cutting edges may be removed collectively for grinding the same.

The rods 88 are adapted to be independently and yieldingly urged outwardly from 45 apertures 97. This is accomplished in the present instance by interposing helical springs 98 which are coiled about the respective rods 88, between suitable enlargements 99 upon the outwardly projecting ends of 50 the rods, and plugs 100 in the opposite ends of apertures 97. Plugs 100 are preferably adapted to be adjusted longitudinally relative to the respective apertures 97, so as to vary the tension of springs 98 as desired, 55 by providing a threaded connection 101 between the plugs and their respective apertures.

Yokes 90, in which the respective rollers 60 are journaled, are instanced as extending 65 outwardly from supporting bar 95 and pro-

vided with depending lugs 103 received in 70 suitable depressions 102 formed in face 83 75 of bar 62 between each adjacent recess 91 or 80 and groove 82. The yokes are guided by the 85 proximate sides of shanks 79 of knives 60, 90 received in grooves 82. Rollers 89 are provided with journal-pins 105 mounted in lugs 103, the parts being preferably so arranged 95 that the rollers are received in recesses 91 with the axes of rotation of the journal pins in substantially the plane of the interrupted cutting edges of knife-blades 80.

The pressure exerted by the rollers against the rear face of the printing plate to be shaved, will thus be applied substantially coincident with the line of the interrupted cutting edge formed by the knife blades. By this arrangement, the printing surface of the printing plate is urged toward its rigid support, instanced as the concave surface of the trough for determining the thickness of the plate which shall be left by the knives as a backing for the printing surface, for reducing the curved printing plate to uniform thickness radially to 90 its printing surface. The pressure exerting devices exerting pressure against the printing plate so as to rigidly hold the same toward the rigid support in substantially the cutting path of the knives, also prevents 95 chattering of the printing plate during the shaving operation.

The material of the printing plate is soft or yielding compared with the support 28 and the flexible plate 29. The pressure devices act to press the printing portions firmly upon the comparatively non-compressible flexible plate 29, so that irregularities in the printing surface are smoothed or ironed out in the area acted on by the cutting edges, which reduce the plate to uniform thickness at its printing portions.

The outward movement of the pressure exerting devices is preferably adapted to be limited by extending the ends of laterally projecting blades 80 of knives 60 within the longitudinal projection of yokes 90, so as to form shoulders 106 upon the knife-blades, against which the ends 107 of the yokes will normally impinge, the parts being so arranged that when the yokes are thus in normal position, the peripheral contacting surfaces of rollers 89 will project slightly beyond the cutting edges of knives 60.

When support 44 is rotated, the shaving parts supported on ledge 54 of the support will be moved across the printing plate 18 positioned in trough 11 by gage 20, so as to shave the rear face 17 of the printing plate, and, due to the cutting engagement between 125 the moving shaving parts and rear face 17, the printing plate 18 and plate 29 beneath the same, will be forced against clamp 19 which forms a stop at the edge of the trough. The clamp is exemplified as a plate 130

extending lengthwise of trough 11 above edge-flange 27 thereof, and having its edge 108 projecting over the inner curved face 28 of the trough when in clamping position, so that the proximate edge 109 of a curved printing plate positioned within the trough, and the edge of sheet 29 beneath the same, will be contacted by the proximate face of projecting edge 108, which is instanced as undercut as shown at 110, to conform to the contour of edge 109 of the printing plate.

Clamping-plate 19 is instanced as pivotally connected, as by hinges 114, to the respective end-walls 35 of the trough, so that the clamping-plate may be swung back out of the way while positioning a printing plate 18 against gage 20 within the trough, the gage being adapted to be contacted by the edge of the printing plate represented at 116 which is opposite edge 109. Plate 19 is adapted to be rigidly clamped in operative position by clamps 115 rotatably mounted upon the respective end-walls 35 of the trough and provided with cam clamping faces 120.

The gage coacting with clamping-plate 19 is exemplified as a plate extending lengthwise of trough 11 within the same and conforming substantially to the curvature of the trough. The gage is instanced as suitably supported so that it may be adjusted along the curvature of trough 11 and clamped at its adjusted positions, so that edge 118 of the gage, adapted to be contacted by edge 116 of printing plate 18, will provide means for positioning the printing plate in the trough.

The supporting means for gage 20 are instanced as arms secured to the opposite ends of the gage and mounted within trough 11 beyond the respective ends of the shaving mechanism. The supporting arms are preferably provided with bearing-enlargements 119 intermediate of their ends. The bearing-enlargements are provided with bearing-openings 121 by means of which the arms are adapted to be rotatably adjusted upon bearing-surfaces 122, instanced as formed upon the outer faces of projections 46 of the bearing-blocks at the respective ends of trough 11. Gage 20 is preferably secured to ends 123 of the supporting arms, which are instanced as extending within trough 11 to a position proximate to plate 29 and outside of the longitudinal projection of the shaving mechanism, so that the gage is adjustably supported between the shaving mechanism and sheet 29. Interference by the gage with the rotary movement of the shaving mechanism is thus avoided.

The opposite ends 124 of the arms supporting gage 20, are preferably connected by a handle-bar 125, so that the arms may be combinedly oscillated upon their respective bearing-surfaces 122. The supporting arms

are instanced as clamped in adjusted positions upon bearing-surfaces 122 by thumb-screws 126. The thumb-screws are preferably supported in threaded apertures 127 in bearing-enlargements 119, and are arranged to clampingly engage the wall of an annular slot 128 in the respective bearing-surfaces 122.

By thus clamping the gage in place it will be positively positioned, so that when a number of printing plates of the same size are to be shaved, the plates may be properly positioned without changing the gage, by successively contacting an edge of the respective plates against the gage.

In operation, the printing plate 18 which it is desired to reduce to uniform thickness at its printing portions, is placed within trough 11, face down, upon plate 29, the printing plate being positively positioned within the trough by gage 20 and clamp 19. The distance between the cutting-path of the cutting edge of the shaving mechanism and plate 29, having been relatively adjusted, by laterally positioning bar 62 upon ledge 54 and by the interposition of paper sheets 31 between the trough and plate 29, support 44 is rotated to move the shaving means across the rear face of the printing plate.

Rollers 89 exerting pressure against the printing plate substantially in line with the interrupted cutting edge of the shaving knives at the interruptions therein, will urge the printing surface of the printing plate toward its support, so that the thickness of the printing portions of the printing plate, acted on by the knives, will be uniform throughout for reducing the printing plate to uniform thickness along spaced apart paths.

By shifting the printing plate lengthwise of its support until the knives are opposite the spaces between the previously shaved paths, the printing plate may be similarly reduced to uniform thickness along such spaces, thus reducing the printing portions of the printing plate to uniform thickness throughout the entire area of the printing plate, and shaving the rear face of the printing plate to a uniform and smooth and regular surface throughout.

If, after a shaving operation as thus described, it is found that the uniform thickness of the printing plate should be further reduced, an additional sheet or sheets 31 may be interposed between plate 29 and trough 11 to accurately adjust the relative distance between the knives and plate 29, and the shaving operation then repeated. The printing plate may thus be accurately reduced to exactly the desired uniform thickness, it being understood that after shaving spaced apart paths in the printing plate at each adjustment of plate 29 relative to the shaving knives, the printing plate is shifted

lengthwise of trough 11 to similarly shave the plate along the spaces between the previously shaved paths, before a further adjustment of plate 29 relative to the knives is made. The shavings are removed through a cleaning hole 131 in the trough.

Having thus fully described my invention, what I claim as new and desire to secure by Letters Patent, is:

10. 1. The method of reducing a printing plate to a uniform thickness at its printing portions, which consists in supporting the printing plate at its printing surface and shaving the rear face of said printing plate a plurality of times in nonincident separated paths while applying pressure to said rear face in the spaces between said paths.
15. 2. The method of reducing a printing plate to a uniform thickness at its printing portions, which consists in supporting a printing plate at its printing surface and shaving the rear face of said printing plate in a line having interruptions therein while applying pressure to said rear face in the interruptions in said line, said pressure applied in an interrupted line which when extended is substantially coincident with said first-named line.
20. 3. The method of reducing a printing plate to a uniform thickness at its printing portions, which consists in supporting a printing plate at its printing surface, shaving the rear face of said printing plate in separated paths while applying pressure to said rear face in the spaces between said paths, causing relative movement between the shaving instrumentalities and said printing plate and shaving along the spaces between the previously shaved portions in the rear face 35 of the printing plate while applying pressure to said previously shaved portions.
25. 4. The method of reducing a printing plate to a uniform thickness at the printing portions of the printing plate, which consists in shaving spaced-apart paths in the rear face of the printing plate while subjecting said plate to pressure between said paths, and then shaving the spaces between said paths while subjecting said previously 40 shaved paths to pressure.
30. 5. In a device of the character described, the combination of a support for a curved printing plate, shaving means having an interrupted cutting edge adapted to be moved across the rear face of said curved printing plate, and means for applying pressure to said rear face located in the interruptions in said cutting edge and in substantial line with said interrupted cutting edge.
35. 6. In a shaving machine for printing plates, the combination of a support for the printing plate, shaving means comprising cutting edges and presser parts alternately arranged for acting on the plate, and means
40. for causing shaving movement between said shaving means and support.
45. 7. In a shaving machine for printing plates, the combination of a support for the printing plate, shaving means comprising cutting edges and presser parts alternately arranged for acting on the plate, said cutting edges being longer than the widths of said presser parts, and means for causing shaving movement between said shaving means and support.
50. 8. In a machine for shaving printing plates, the combination of a rigid supporting face in the form of the sector of a cylinder, a flexible supporting plate of uniform thickness for the outer face of a curved printing plate, means for securing said printing plate relative to said supporting face, shaving means adapted to be moved across the rear face of said printing plate, and means for relatively adjusting the distance between said supporting plate and said shaving means.
55. 9. In a device of the character described, the combination of a support for a curved printing plate, a support for shaving means extending lengthwise of said first-named support, a bar upon said second-named support, spaced-apart shaving means upon said bar forming an interrupted cutting edge extending lengthwise of said supports, and means for adjusting said bar upon said second-named support.
60. 10. In a machine for shaving printing plates, the combination of a support for the printing plate, and shaving means for the printing plate comprising knives and presser parts arranged end to end, said knives being of greater width than the width of said presser parts, whereby the paths of said knives overlap during a plurality of shaving operations between said printing plate and knives.
65. 11. In a machine for shaving printing plates, the combination of a support for the printing plate, shaving means for the printing plate comprising knives and presser parts arranged end to end, said knives being of greater width than the width of said presser parts, whereby the paths of said knives overlap during a plurality of shaving operations between said printing plate and knives, and said presser parts normally extending beyond the cutting edges of said knives.
70. 12. In a machine for shaving printing plates, the combination of a support for the printing plate, shaving means for the printing plate comprising knives and presser parts arranged end to end, said knives being of greater width than the width of said presser parts, whereby the paths of said knives overlap during a plurality of shaving operations between said printing plate and knives, said presser parts normally extend-

- ing beyond the cutting edges of said knives, and means for limiting outward movement of said presser parts.
13. In a machine for shaving printing plates, the combination of a support for the printing plate, shaving means for the printing plate comprising knives and presser parts arranged end to end in repeated alternation, said knives being of greater width than the width of said presser parts, said presser parts normally extending beyond the cutting edges of said knives, and means for adjusting the pressures of said presser parts.
14. In a machine for shaving printing plates, the combination of a rigid support for the printing plate, shaving means for the printing plate comprising knives and presser parts arranged end to end in repeated alternation, said knives being of greater width than the width of said presser parts, said presser parts normally extending beyond the cutting edges of said knives, means for adjusting the pressures of said presser parts, and means for moving said shaving means toward and from said rigid support.
15. In a machine for shaving printing plates, the combination of a support for the printing plate, and shaving and pressure means comprising knives and presser rollers alternately disposed lengthwise of said support, the contact lines of said knives and presser rollers with the printing plate on said support being substantially coincident.
16. In a machine for shaving printing plates, the combination of a support for the printing plate, shaving and pressure means comprising knives and presser rollers alternately disposed relatively to said support, the contact lines of said knives and presser rollers with the printing plate on said support being substantially coincident, and the said knives being wider than said presser rollers.
17. In a shaving means for printing plates, the combination of a rigid support, a flexible plate for said support, shaving means comprising cutting edges and presser parts alternately arranged end to end for acting on the plate, means for adjusting said flexible plate toward and from said support, and means for causing shaving movement between said shaving means and said support.
18. In a machine for shaving curved printing plates, the combination of a rigid support having a supporting surface of substantially the form of a sector of a cylinder, an auxiliary flexible non-compressible supporting plate complementary to said rigid support, shaving means having a path of movement concentric with said supporting surface, a gage for a curved printing plate adjustable between said path of said shaving means and said rigid supporting surface, said shaving means and said gage having coincident axes, and a clamp coacting with said gage and forming a stop for said printing plate during the shaving operation.
19. In a machine for shaving curved printing plates, the combination of a support having a supporting surface curved along the curvature of a sector of a cylinder, shaving means having a path of movement concentric with said sector of said cylinder, a gage supported for movement in a path concentric with said first-named path between said first-named path and said supporting surface, a stop coacting with said gage, and means whereby to adjustably position said gage, and said shaving means and gage having coincident axes.
20. In a machine for shaving curved printing plates, the combination of a support having a supporting surface curved along the curvature of a sector of a cylinder, shaving means having a path of movement concentric with said sector, and a gage supported for movement in a path concentric with said first-named path between said first-named path and said supporting surface, means whereby to adjustably position said gage, and a clamp coacting with said gage for clamping the curved printing plate.
21. In a machine for shaving printing plates, the combination of a support for the printing plate, and shaving means for the printing plate comprising knives and presser parts arranged alternately end to end, said presser parts arranged for combined removal from said machine.
22. In a machine for shaving printing plates, the combination of a support for the printing plate, a second support, a bar, cutting means thereon, a second bar, presser means thereon, said cutting means and presser means when assembled arranged alternately lengthwise of said supports, and means for removably securing one of said bars and both of said bars to said second support.
23. In a device of the character described, the combination of a curved supporting surface for the outer face of a curved printing plate, a support extending lengthwise of said curved supporting surface, means for causing relative rotary movement between said support and said curved supporting surface, shaving means upon said support comprising a plurality of cutting edges extending lengthwise of said curved supporting surface, said cutting edges having spaces between them, said cutting edges being uniformly spaced from said curved supporting surface during said relative movement between said support and said curved supporting surface, and pressure exerting means upon said support yieldingly urged in said first-named spaces toward said curved supporting surface.

24. In a device of the character described, the combination of a support for a printing plate, a longitudinally extending supporting member, shaving knives projecting from said supporting member, said shaving knives having spaces between them, and independent pressure exerting means in said spaces normally urged outwardly beyond the cutting edges of said shaving knives.
- 10 25. In a device of the character described, the combination of a support for a printing plate, a longitudinally extending supporting member, shaving means comprising knives projecting from said supporting member in longitudinally spaced relation, said knives forming an interrupted cutting edge extending lengthwise of said supporting member, recesses in said supporting member between adjacent knives, and pressure exerting devices received respectively in said recesses, said pressure exerting devices normally urged outwardly beyond said cutting edge at the interruptions therein and in the plane of said knives.
- 15 26. In a device of the character described, the combination of a support for a printing plate, a longitudinally extending supporting member, shaving means projecting outwardly from said supporting member and forming an interrupted cutting edge lengthwise of said supporting member, pressure exerting devices between adjacent shaving means, said pressure exerting devices yieldingly urged outwardly beyond said cutting edge at the interruptions therein, means upon said pressure exerting devices arranged to contact said adjacent shaving means to limit the movement of said pressure exerting devices beyond said cutting edge.
- 20 27. In a device of the character described, the combination of a curved support for the outer face of a curved printing plate, shaving means spaced from said support and extending lengthwise thereof, said shaving means adapted to be moved across the rear face of said curved printing plate, a gage extending lengthwise of said support between the path of said shaving means and said support, said gage being adjustable along the curvature of said curved support, and means for locating said gage in adjusted positions.
- 25 28. In a device of the character described, the combination of a curved support for the outer face of a curved printing plate, bearings at opposite ends of said support, shaving means extending lengthwise of said support and journaled in said bearings, said shaving means spaced from said support and adapted to be moved across the rear face of said curved plate, a gage extending lengthwise of said support between the path of said shaving means and said support, supports for said gage journaled on said bearings beyond the respective ends of said shaving means whereby to adjust said gage along the curvature of said curved support.
- 30 29. In a machine for shaving printing plates, the combination of a support for the printing plate, a supporting bar, shaving means for the printing plate comprising knives and presser devices mounted upon said bar and alternately disposed lengthwise thereof, said presser devices arranged for combined removal from said supporting bar.
- 35 In testimony whereof, I have hereunto signed my name in the presence of two subscribing witnesses.
